ELECTRODE ASSEMBLY

Harry A. Wintermute, Plainfield, N. J., assignor
to Research Corporation, New York, N. Y., a
corporation of New York

Application June 3, 1946, Serial No. 674,139

3 Claims. (Cl. 183—7)

1

This invention relates to electrode assemblies for electrical precipitators and more particularly to electrode assemblies including a filamentary scraper element for removing precipitated particulate matter from cylindrical collecting electrodes of an electrical precipitator.

An object of the invention is to provide improved means for cleaning electrodes, from which, as is well known, adherent dust or other precipitated material must be periodically removed in order to maintain high operating efficiency of the electrical precipitator.

Another object is to provide a filamentary or wire scraping member for a cylindrical electrode which is constructed and arranged for relative movement over the surface of the electrode to scrape precipitated matter from the electrode surface.

Other objects are to provide simple means for supporting the filamentary scraper in effective scraping relation to the electrode surface and to provide conveniently operable and easily manufactured and maintained mechanism for causing relative movement between the cylindrical electrode member and the scraper element.

In a characteristic embodiment, the invention takes the form of an electrode assembly in an electrical precipitator which comprises an electrode member, a filamentary scraping element mounted in contact with the surface of said electrode member, and means for causing relative movement of said filamentary element in respect to and over the surface of said electrode member. In a preferred embodiment, the electrode element is cylindrical, is mounted for rotation about its longitudinal axis, and has means for causing its rotation; and the scraping element is a metallic wire resiliently and relatively fixedly mounted in helical contact with the cylindrical surface of the electrode member. As the electrical precipitators to which the invention is applied usually have a plurality of cylindrical electrodes, the invention may include means for rotating the electrodes in unison and means for mounting a plurality of scraping elements, each in contact with one of the cylindrical electrodes.

The invention will be more particularly described and other of its objects and advantages will appear in the following detailed description of one of its embodiments, as shown in the accompanying drawings. In the drawings:

Fig. 1 is a vertical sectional view taken through an electrical precipitator along a plane parallel to the direction of gas flow;

Fig. 2 is a plan view, on a reduced scale, of the

2

precipitator shown in Fig. 1, parts being broken away to show interior construction, and

Fig. 3 is a sectional view, on the same scale as Fig. 2, taken along the plane of the line 3—3 of Fig. 1.

Referring to the drawings, wherein like reference numerals refer to like parts in the several views, the electrical precipitator shown has a housing 10 provided with a base panel 11, side walls 12, and a top 13. The front and back walls 14 rise from the base only a short distance, as best seen in Fig. 1, to provide with the base panel and lower portions of the side walls a sump or pit 15 into which settles dust or other matter scraped from the electrodes. Access to the sump may be had through a door 16 for periodic cleanouts.

The front and back of the housing are open to provide a passageway for circulation of gas to be cleaned, the gas stream flowing through the apparatus in the sense of the arrow shown in Fig. 1. It will be understood that the precipitating unit shown, or a number of them arranged in series, is provided with conduit means (not shown) for leading a stream of gas to be cleaned to the precipitator and for carrying away the stream of cleaned gas. A fan or other circulating means (not shown) may be provided.

Within the housing there are disposed two banks of complementary electrodes, the collecting electrodes 17 being cylindrical extended surface electrodes and the high tension electrodes 18 being fine wire discharge electrodes. The high tension electrodes are insulated from the casing and from the extended surface electrodes and are supplied, in a manner to be explained, with high tension electric current. The extended surface electrodes are grounded to the casing, which in turn is grounded; or these electrodes are otherwise maintained at a suitable preselected potential to generate, in cooperation with the fine wire electrodes, a high tension electric field accompanied by corona discharge. As will be understood by persons skilled in the art, particles suspended in a stream of gas passing through the apparatus acquire an electric charge and are largely attracted to the extended surface electrodes upon which they are deposited as an adherent film.

The means for supporting the high tension electrodes 18 and for insulating them includes a pair of laterally disposed tubular insulating members 19, preferably formed of a synthetic resinous material, porcelain, or the like. The insulating members are received in holes formed in the side walls 12 and secured in position by

adjustable collars 20. The insulating support members 19 carry a pair of vertically disposed struts 21, the struts being preferably formed of conducting metal and being fastened to the support members 19 by means of screws 22, as best seen in Fig. 1. Horizontal metallic beams 23 are welded to the tops and bottoms of the struts 21, and the beams, in turn, have welded to them a plurality of spaced metallic cross-arms 24. The fine wire electrodes are tensioned between the ends of the cross-arms, as shown. There is thus provided an insulated high tension electrode assembly to which high tension current may be led through any suitable conductor (not shown). If desired, the conductor may be run into one of the insulating tubes 19 and connected to one of the screws 22 to supply current to the high tension electrode assembly.

The cylindrical extended surface electrodes 17 are mounted for rotation about their longitudinal axes. To provide for this mounting, they are journalled at their lower ends in bearings 25 carried by the horizontal members 26 and at their upper ends in bearings 27 carried in the top 13 of the housing.

Mechanism is provided for rotating the cylindrical electrodes 17 in unison. Such mechanism includes the cranks 28 extending from the upper end of each of the electrodes. The offset arms 29 of the cranks are slidably received in holes 30 formed in a tie-plate 31, the holes being spaced on centers corresponding to the horizontal spacing of the cylindrical electrodes. It will thus be seen that circular motion imparted to the tie-plate will cause rotation of the cylindrical electrodes through the agency of the cranks 28.

A main driving crank 32 is provided for imparting to the tie-plate the requisite circular motion. The crank is journalled in a lower bearing 33 and in an upper bearing 34, the latter being formed in a bearing plate 35 supported on the top 13 of the housing by upright members 36. As shown, the driving crank is manually operable, but it will be understood that continuous or intermittent power driving means may be used advantageously in some installations.

There is provided for each extended surface electrode a filamentary scraping element 37 which bears against the cylindrical surface of the electrode and is relatively fixedly mounted with respect to the electrode. The scraper wires are preferably resiliently mounted under tension, and, as shown in the drawings, the upper and lower ends of the wires are affixed to bow-springs 38 and 39, respectively, the springs being mounted on bosses 40 and 41 to which they are fastened by screws.

The scraping wires 37 are held in contact with the cylindrical surfaces of the extended surface electrodes 17 preferably along a helical path of high pitch. In the illustrative embodiment shown, the wire makes one-half of a turn about the cylinder, but other pitches may be used. Conveniently in the modification shown, one, one and one-half, or two turns of the wires about the cylinders can be utilized successfully.

Various materials may be used for the filamentary scraping elements such as soft copper enameled wire, iron wire, fibrous filaments, or synthetic filaments. Also, the specific means shown for supporting the scraping elements may be varied as desired in the light of the foregoing description. Coil springs or other resilient mounting means may be used to support one or both ends of each scraping wire, or, if the wire

has sufficient inherent resiliency, separate resilient mounting means may be omitted.

In operation, as precipitated material builds up on the electrodes 17 to a point where efficiency of precipitation is likely to be impaired, it is only necessary to turn the crank 32 through one or two revolutions to scrape the electrodes clean and thus to re-establish optimum precipitation conditions. Material scraped from the electrodes falls into the sump 15 from which it may be removed as necessary through the door 16.

In the construction shown, it is a relatively simple matter to replace damaged or broken scraping elements by merely detaching the undesired filaments from the bow-springs 38 and 39 and replacing them with new ones.

From the foregoing description it will be seen that there has been provided an improved electrode assembly including an electrode scraping device which eliminates the necessity for employing electrode rapping or flushing devices and which is characterized by the employment of a filamentary scraping element which can be maintained in intimate contact with the surface of an electrode whereby the electrode surface may readily be maintained in a substantially clean condition so that back discharge is obviated.

I claim:

1. In an electrical precipitator including complementary high tension and extended surface collecting electrodes, said extended surface electrode comprising a cylindrical electrode member having its external convex surface disposed in complementary relation to said high tension electrode, means mounting said cylindrical electrode member for rotation about its longitudinal axis, and means for rotating said cylindrical electrode member; a filamentary scraping element, and means relatively fixedly mounting and tensioning said filamentary scraping element in helical contact with the convex surface of said cylindrical electrode member.

2. In an electrical precipitator including complementary high tension and extended surface collecting electrodes, said extended surface electrode comprising a cylindrical electrode member having its external convex surface disposed in complementary relation to said high tension electrode, means mounting said cylindrical electrode member for rotation about its longitudinal axis, and means for rotating said cylindrical electrode member; a filamentary scraping element, and resilient means relatively fixedly mounting and tensioning said filamentary scraping element in helical contact with the convex surface of said cylindrical electrode member.

3. An electrical precipitator comprising a pair of substantially coextensive spaced parallel cylindrical collecting electrodes, high tension electrode means positioned in complementary relation to the external convex surfaces of said cylindrical collecting electrodes, means mounting each of said cylindrical electrodes for rotation about its axis, means for rotating said cylindrical electrodes, bow-spring members extending transversely across the gaps between the ends of said cylindrical electrodes, means fixedly mounting said spring members substantially at their midpoints, and filamentary scraping elements tensioned between said bow-spring members in helical contact with the convex surfaces of said cylindrical electrode members.
